(57) **CLAIM**

The ornamental design for an insulated framing lumber, as shown and described.

DESCRIPTION

FIG. 1 a perspective view of a first embodiment of an insulated framing lumber showing the new design;
FIG. 2 is another perspective view thereof;

FIG. 3 is a top view thereof;
FIG. 4 is a bottom view thereof;
FIG. 5 is a front view thereof;
FIG. 6 is a back view thereof;
FIG. 7 is a right side view thereof;
FIG. 8 is a left side view thereof;
FIG. 9 is a perspective view of a second embodiment thereof;
FIG. 10 is another perspective view thereof;
FIG. 11 is a top view thereof;
FIG. 12 is a bottom view thereof;
FIG. 13 is a front view thereof;
FIG. 14 is a back view thereof;
FIG. 15 is a right side view thereof;
FIG. 16 is a left side view thereof;
FIG. 17 is a perspective view of a third embodiment thereof;
FIG. 18 is another perspective view thereof;
FIG. 19 is a top view thereof;
FIG. 20 is a bottom view thereof;
FIG. 21 is a front view thereof;
FIG. 22 is a back view thereof;
FIG. 23 is a right side view thereof;
FIG. 24 is a left side view thereof;
FIG. 25 is a perspective view of a fourth embodiment thereof;
FIG. 26 is another perspective view thereof;
FIG. 27 is a top view thereof;
FIG. 28 is a bottom view thereof;
FIG. 29 is a front view thereof;
FIG. 30 is a back view thereof;
FIG. 31 is a right side view thereof; and,
FIG. 32 is a left side view thereof.

The broken lines depict environmental subject matter that forms no part of the claimed design. The drawings show symbolic break-lines along the height, width and depth of the insulating framing lumber. The break-lines and the spaces in between the break-lines form no part of the claimed design. The break lines and brackets are graphical symbols which form no part of the claimed design.

1 Claim, 20 Drawing Sheets
